(57) **CLAIM**

The ornamental design for a bicycle fender, as shown and described.

DESCRIPTION

FIG. 1 is a front top left perspective view of a bicycle fender showing my new design;

FIG. 2 is a front bottom left perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof; and,

FIG. 9 is an enlarged cross-sectional view taken along the line 9-9 of FIG. 1.

The broken lines in the figures are to show portions of the bicycle fender and form no part of the claimed design.

The dashed broken lines depict portions of the bicycle fender that form no part of the claim. The dot-dash lines on FIGS. 1-8 define the bounds of the claim and form no part of the claimed design.

1 Claim, 8 Drawing Sheets
